CRUSHING MACHINE

John E. Dick, Hallock, Minn.

Application June 29, 1936, Serial No. 87,926. Renewed December 23, 1938. In Canada June 29, 1935

9 Claims. (Cl. 83—8)

This invention relates to improvements in feed crushing machines and an object of the invention is to provide a device of the character herein described which is simple and rugged in construction and in which no damage can result to the device in the event of a damaging obstruction being encountered during the process of grinding.

A further object of my invention is to provide a device of the character herein described in which the feeding member therein will cease to rotate when a damaging obstruction has been received within the machine.

A further object of my invention is to provide a device of the character herein described in which means are provided for regulating the amount of material admitted to the feed chamber.

A further object of my invention is to provide a device of the character herein described, in association with which, an arcuate blade is provided for the purpose of assisting in the conveyance of obstructive material into a compartment provided for this purpose.

A further object of my invention is to provide a device of the character herein described in which foreign matter will be separated from the feed and may be removed from the machine.

A further object of my invention is to provide a device of the character herein described which is simple to construct, economical to manufacture and will not easily become out of order.

With the above more important objects in view and such other minor objects as may appear as the specification proceeds, my invention consists essentially in the arrangement and construction of parts all as hereinafter more particularly described, reference being had to the accompanying drawings, in which:

40 Fig. 1 illustrates a vertical sectional view of my improved type of feed crusher.

Fig. 2 shows a side view of the feed member used therein.

Fig. 3 is a fragmentary horizontal sectional view taken on the line 3—3 Figure 1.

Fig. 4 is a vertical sectional view of my feed crusher taken on the line 4—4 Figure 1.

Fig. 5 is a sectional elevational view taken on the line 5—5 Figure 3.

50 Fig. 6 illustrates a portion of the face of one of the grinding discs used in my invention.

Fig. 7 illustrates a fragmentary sectional view of a second embodiment of my device.

Fig. 8 is a vertical sectional view taken on the 55 line 8—8 Figure 7.

Fig. 9 is a vertical sectional view taken on the line 9—9 Figure 7.

Fig. 10 shows a horizontal sectional view of the thrust bearing and associated mechanism as used in the second embodiment of my invention. 5

Fig. 11 is a sectional view taken on the line 11—11 Figure 10.

In the drawings like characters of reference indicate corresponding parts in the different figures. 10

This invention consists of a feed chamber 1 having vertical front and rear walls 2 and 3 respectively, and downwardly converging side walls 4. Flanges 5 extend outwardly from the lower edges of the side walls, and are reinforced by 15 ribs 6.

Hingedly attached to one of the flanges 5 is a longitudinally extending trap door 7 to which is attached a downwardly disposed arm 8, adjacent the hinges 9. A tensile spring 10 extends between the lower end of the arm 8 and the opposite flange 5 and tends to keep the door 7 normally in a closed position, as illustrated in Fig. 4 of the accompanying drawings.

Attached to the upper edges of the wall which 25 surrounds the feed member is a hopper 11, the front wall 12 of which is vertically disposed, whereas the side and rear walls 13 diverge upwardly.

Extending horizontally from the lower edge of 30 the rear end wall 3 is a plate 14 carrying an annular member 15 which is supported by a web 16. Within this member is inserted a self-aligning bearing 17 held in position by the oil duct 18 leading from the oil cup 19 and extending 35 through the member and into the bearing.

An orifice 20 is formed within the rear wall 3 of the feed chamber in alignment with the axis of the bearing 17 and a second orifice 21 of somewhat larger diameter than the orifice 20 is provided in the front wall 2 in direct opposition to the first mentioned orifice. 40

Protruding outwardly from the front wall 2 at an equal distance from the centre of the orifice 21 are a plurality of drilled bosses 22 which are 45 designed to permit the rear portion 23 of the crushing chamber to be attached to the device. This portion of the crushing chamber comprises an encircling flange 25, to the inner edge of which is attached an annular plate 26 having a converging ring 27 integrally fastened thereto, which is designed to fit snugly within the orifice 21, a short flange 28 extends centrally from the inner edge of the ring 27. 50

Abutted against the edge of the rear portion 55

of the crushing chamber and fastened thereto by bolts 29 is a closure 30 consisting of a flange 31 similar to the flange 25 to which is attached a converging frusto conical portion 32 having a short cylinder 33 integrally fastened to, and extending forwardly from, the edge thereof. A narrow ring 34 is affixed to the forward end of the cylindrical portion 33 which, together with said portion forms an annular chamber 35 there-
10 within. An outlet spout 35' is provided in the side of the crushing chamber through which crushed material may pass.

Slidably mounted centrally within the ring 34 is a sleeve 36, the inner end of which, is provided with a flange 37. A compression spring 38 is placed within the recess 35 and bears against the inner surface of the ring 34 and the flange 37. It should be noted that by virtue of the method of mounting the sleeve 36 acts as a self-aligning bearing for a shaft presently to be described.

Inserted within the end of the sleeve 36 is a short cylinder 39 having a tapped orifice 40 passing centrally therethrough. An oblique slot 41 is provided within this cylinder and is adapted to engage with the inner end of a bolt 42 which passes through the wall of the sleeve 36. Upon the outer end of the cylinder is attached an arm or finger 43 by means of which the cylinder may be rotated within the limits of the slot 41.

30 A threaded shank 44 is passed through the orifice 40 and the inner end thereof is provided with a thrust bearing 45. A hand wheel 46 is attached to the outer end of the shank for operating purposes. Also mounted upon the shank is a locking nut 47 furnished with an arm 48 by means of which the nut may be made to bind against the outer surface of the cylinder 39 to hold the shank in any desired position.

Mounted within the bearing 47 and the sleeve 36 is a central shaft 49 one end of which bears against the thrust bearing 45. The opposite end of the shaft is provided with a belt pulley 50 by means of which power may be supplied to the machine.

45 Attached to the shaft adjacent the bearing 47 is a sleeve 51 which is permitted to slide longitudinally thereon by means of a Woodruff key 52 which engages with a slot 53 on one side of the central orifice 54. This orifice is enlarged as at 55, the outer end thereof being designed to receive a portion of the bearing 47. A compression spring 56 is interposed between the bearing and the shoulder 57 formed by the junction of the orifices 54 and 55.

55 Attached to the forward portion of the sleeve 51 as an annular flange 58 which is designed to close the orifice 20 but to allow a slight tolerance between the edge thereof and the flange in order that the latter member will not touch the edge of the orifice while rotating.

60 Integrally attached to the forward end of the sleeve 51 is a converging or frusto conical portion 59 which is undercut to provide a chamber 60.

65 Mounted on the shaft 49 within the crushing chamber is a circular plate 61 which is mounted upon a hub 62. This hub, it will be noted, extends somewhat rearwardly of the plate and converges toward the end thereof. This plate 61 is 70 normally maintained in driving engagement with the shaft 49 and is locked against forward axial movements thereon by means of the pin that is passed through the shaft and through the forward end of the hub 62. Mounted upon the face 75 of the plate by means of bolts 63 is a rotating

grinding disc 64 which is provided on the grinding surface with a plurality of crossed furrows as shown in Fig. 6. This plate tapers toward the centre as clearly shown in Fig. 1. Directly opposed to the rotating disc is a second grinding disc 65 which is similar in every detail to the first mentioned disc and securely attached by bolts 66 to the inner surface of the casing of the grinding chamber 24.

The centrally converging surfaces of the two 10 grinding discs, it will be noted, leave an encircling mouth between the discs through which the material to be ground may pass.

Extending between the hub 62 and the frusto conical portion 59 of the sleeve 51 is a forwardly 15 diverging hollow feed member 67. This member is provided with a spiral flange 68 extending from the rear end to the front end thereof, this flange being gradually reduced with respect to the distance between its crown and its root as it continues toward the front end of the member.

At the forward enlarged end of the member two further flanges 69 and 70 are provided so that at this end it will be noted, the flanges are much closer together than at the rear reduced end 25 of the sleeve.

The forwardly diverging hollow feed member 67 with its spiral flanges 68, 69 and 70 forms a tapered hollow feed screw.

The forward end of this sleeve is designed to 30 fit snugly over the hub 62 but may slide thereon under certain conditions to be later explained. The rear end of the hollow feed screw, however, is flared as at 71 and is complementarily formed with respect to the frusto conical portion 59 upon 35 the shaft driven sleeve 51. The feed screw is made to rotate with the sleeve and consequently the shaft, in accordance with the present illustration, by means including a pin 72 which passes through the flared portion 71 and the frusto conical portion 59 and the engaged conical surface of the sleeve 59 and the feed screw. This pin may be either made to fit snugly within the recipient orifices or it may be threadably attached therein and it is designed when an obstruction enters the 40 machine to shear off, thereby stopping rotation of the feed member and preventing further damage to the machine.

45 It should be understood that the spring 56 maintains the feed member driving sleeve 51, the 50 hollow feed screw and the plate 61 under axial compression therebetween and the pin that extends through the shaft and hub 62. Obviously this yielding compression exerted by the spring 56 keeps the forward end of the hollow feed screw 55 tightly pressed on to the hub 62 and the flared conical rear end 71 of the feed screw in tight frictional engagement with the conical portion 59 of the sleeve 51.

60 Encircling the enlarged end of the feed member 67 is a collar 73 provided with an encircling shoulder 74 extending around the outer periphery thereof, this shoulder being adapted to bear normally against the inner surface of the flange 28. It should be noted that the central passage- 65 way through the collar diverges in accordance with the divergence of the feed member, and is adapted to have a somewhat greater radius at any point than that of the crown of the adjacent ribs which encircle the feed member.

70 Preferably, and as illustrated in the drawings, the inside radius of the collar at any point will be just sufficiently greater than that of the corresponding maximum diameter portion of the screw to provide free working clearance.

The collar 73 is normally held in the position illustrated in Fig. 1 by means of a spring clip 75 having a U-shaped configuration, the ends of which are turned to pass through diametrically opposed orifices 76 within the ring 27 and to bear against the forward surface of the shoulder 74.

In the event, however, of a damaging obstruction entering between the feed screw and the collar, the pressure of this obstruction will 10 distend the spring clip 75 and allow the collar to move forwardly to ultimately bear against the surface of the plate 61, thereby preventing the passage of any further material between the grinding discs.

15 In order to adjust the quantity of material admitted to the feed chamber in a given time, a partition 11 extends horizontally across the chamber above the feed member 67. This partition is provided with an aperture 18 extending 20 across the rear end thereof which is closed by a sliding door 79 mounted upon guides 80 and 81 attached to the side walls 4. This door is actuated by a manually operated rod 82 which passes through an orifice 83 in the door. In order that 25 the door will remain in any set position, a spring leaf 84 is attached to the under side of the partition 11. The free end 85 of this leaf is turned and is designed to bear against the surface of the door 79 to prevent accidental shifting thereof.

30 In Figs. 7 to 10, inclusive, I have illustrated details which may be used in conjunction with the machine already described if desired.

Fig. 7 shows a feed screw 86, shaft 87, grinding chamber 88 and grinding plates 89 all identical to those already described in this application. However, instead of the side walls converging downwardly from the feed hopper, they are dropped vertically as at 90 and are curved beneath the feed screw in the manner shown

40 most clearly in Fig. 9. It should be noted that the left hand wall extends downwardly farther than the right hand wall at the rear of the device, the lower edge 91 thereof being joined to the edge of the right hand wall by a vertical strip 92. This forms a longitudinally extending trough 93 which opens downwardly into a short channel 95 bounded by walls 92 and 95 as clearly illustrated in Fig. 8 of the accompanying drawings.

50 A discharge aperture 96 is provided in the bottom of the channel and is normally kept closed by a trap door 97 maintained in position by an angulated spring leaf 98.

Hingedly mounted within the trough 93 and 55 adjacent the side of the channel 94 is a longitudinally extending arcuate blade 99 held in the upright position illustrated by means of a curved strap spring 100 which is attached to the floor of the trough by a rivet 101.

60 In Figs. 10 and 11 I have illustrated a further method of attaching the thrust bearing 102. This consists of inserting into the sleeve 103 which corresponds to the sleeve 45 in the structure already described, a bushing 104 having a pair of 65 opposed lugs 105 extending diametrically therefrom. The bushing is centrally tapped to receive a threaded shank 106 which carries the thrust bearing 102 on the inner end thereof. This bearing is designed to engage with the central shaft 107 in order that the shaft may move forwardly in the event of a damaging obstruction entering between the grinding plates. Bolts 108 are passed through the lugs 105 and also through corresponding ears 109 made integral with the 70 sleeve 103. Nuts 110 are attached to the ends of

the bolts and compression springs 111 are inserted between the nuts and the ears 109 and maintain the bushing normally in the position shown in Fig. 10.

75 In order that the shank 106 may be maintained in any desired position a locking nut 112 is mounted thereon and is provided with a short projecting finger 113 by means of which the nut may be adjusted.

Having described the structure of my device, 10 the mode of operation will now be presented.

The pulley 50 is attached by means of a belt to a source of energy, and material to be crushed is then dumped into the hopper 11. The door 79 is now opened by the rod 82 and the material admitted to the feed chamber 1. The feed screw is at this time rotating at a high rate of speed, and the spiral flanges 68, 69, and 70 urge the material through the collar 73 into the grinding chamber where it is flung between the plates by centrifugal force. The substance is now ground between the grinding discs and is then expelled therefrom after which it passes through the outlet spout 35' attached to the side of the grinding casing.

25 In the event, however, of a damaging obstruction endeavouring to enter through the collar 73, this obstruction will bind between the collar and one of the spiral flanges and the collar will be urged forwardly to bear ultimately against the 30 rotating grinding plate in the manner already described. The collar will now be rotated by the feed member and the friction thereof will cause a considerable retarding force to the feed member which, if not stopped, will shear off the pin 72 35 and thus disconnect the feed member from the rotating mechanism. The larger end of the feed screw will at this time simply slide upon the hub 62.

40 In the case of a small obstruction which passing through the collar 73 might damage the grinding plates, immediately it passes between the plates, the rotating disc moves outwardly against the pressure of the spring 38. In this manner, the distance between the discs is increased and any damage thereto is prevented.

45 It should be noted that the space between the discs may be adjusted to suit any conditions by changing the position of the thrust bearing by means of the shank 44. The shank may be then 50 locked in any location by the nut 47. If for any reason it is desired to suddenly increase the distance between the grinding discs, it is necessary only to rotate the finger 43 which will move the cylinder 39 forwardly by virtue of the bolt 42 and 55 the slot within the cylinder.

While the grinding operation is in progress, any heavier bits of material will fall into the chamber beneath the feed member and when sufficient material has accumulated there, the 60 trap door may be opened and the material expelled. The arcuate blade 99 illustrated in Figs. 7, 8, and 9 has been found very effective in preventing idle churning of material below the feed member and the trap door 97 performs the same 65 function as the door 7 already described. It is important to note in connection with each of the several forms of the invention illustrated that the feed screw and the feed screw passage to the crushing chamber are located very materially 70 above the bottom of the feed chamber so that any heavy foreign substance which gravitates to a level below the feed screw while in the feed chamber will become trapped in this lower portion of the feed chamber. This feature is impor- 75

tant in spite of the fact that novel means is to move into engagement with one of said crush-
herein provided for preventing damage in caseing plates, said last mentioned means consisting
of an obstruction, since the preventing of obstruc-
tion will greatly reduce the frequency of inter-
ruptions in service. 5

In this connection it is further important that
the feed screw be extended substantially from
front to rear end of the feed chamber and that
the inlet to the feed chamber be confined to the
10 rear end portion thereof. With this construc-
tion the material ultimately delivered to the
feed chamber outlet passage to the crushing
chamber will essentially be churned and agitated
15 considerably during its longitudinal movement
between the inlet and outlet and this period of
agitation will result in the gravitation to a level
below the feed screw and outlet passage of sub-
stantially all foreign substances having a spe-
20 cific gravity greater than the material being
ground. Hence, most or practically all foreign
substances such as stones, nails and the like will
become trapped in the bottom of the feed cham-
ber where they can do no harm to either the feed
25 or crushing mechanism.

25 The pressure releasing mechanism illustrated
in Fig. 10 may, if desired, be used to replace the
spring 38 at which time the sleeve 36 would be
firmly held within the flange 34.

From the foregoing it will now be evident that
30 I have provided an ingenious type of crushing
machine which, while being adapted to crush ma-
terial very efficiently, is also provided with nu-
merous safety means to prevent damage to the
machine while in operation.

35 Since various modifications can be made in
the above invention, and many apparently wide-
ly different embodiments of same made within
the scope of the claims without departing from
the spirit and scope thereof, it is intended that
40 all matter contained in the accompanying speci-
fication shall be interpreted as illustrative only
and not in a limiting sense and I desire only such
limitations placed thereon as are specifically ex-
pressed in the accompanying claims.

45 What I claim as my invention is:

1. Improvements in crushing machines com-
prising a housing contained a crushing chamber
and feed chamber, a feed member extending
50 through said feed chamber and into said crush-
ing chamber, means for preventing a damaging
obstruction entering said feed chamber consist-
ing of a movable collar circumscribing said feed
member, said collar being normally held in position
55 by means of resilient means extending be-
tween said collar and said housing, means for
causing the feed member to cease rotating upon
a damaging obstruction entering said feed cham-
ber, a crushing plate attached to said housing and
60 a further plate in association with said feed
member, all in association with said device.

2. Improvements in crushing machines com-
prising a housing enclosing a feed chamber and
a crushing chamber, a shaft mounted upon self-
aligning bearings extending through said feed
65 chamber and said crushing chamber, a tapered
sleeve mounted upon said shaft, a spiral flange
extending around said sleeve, a member slidably
keyed to said shaft, means for attaching said
sleeve to said member, a crushing plate in asso-
70 ciation with said feed member, a further aligned
crushing plate opposing said first mentioned
crushing plate, means for preventing the en-
trance of a damaging obstruction into said
crushing chamber consisting of a collar encir-
75 cing said sleeve, means for allowing said collar

5 to move into engagement with one of said crush-
ing plates, said last mentioned means consisting
of a pin maintained in engagement with said
collar by resilient means and means in associa-
tion with said feed chamber for allowing the
outlet of foreign material from said feed cham-
ber. 5

3. Improvements in crushing machines com-
prising the combination with a main casing in-
cluding a feed chamber, a crushing chamber and
crushing means within said chamber of a rotat-
able tapered feed member extending through said
casing from front to rear thereof, said member
10 being mounted upon a shaft extending through
orifices upon the front and rear walls of said cas-
ing, said member being provided with a spiral
flange thereupon, a collar surrounding said mem-
ber, normally contained within the diameter of
15 said orifice upon said front wall of said casing,
said collar co-acting with said feed members and
releasing means for permitting rotation of said
collar upon the attempted passage of a damag-
ing obstruction into said crushing chamber, said
tapered feed element being in the form of a hol-
20 low sleeve, the crown of said spiral flange taper-
ing with but at a lesser rate than said sleeve,
said collar being provided with a flared out inner
periphery. 25

4. In a device of the kind described, a power
driven shaft having a concentric hub element
30 thereon, a sleeve axially slidable on the shaft in
axially spaced relation to said hub element and
being in rotary driving engagement with said
shaft, said sleeve carrying an external conical
clutch surface that converges in the direction of
35 said hub element, a hollow feed screw telescopi-
cally applied on said shaft intermediate said
sleeve and hub element with one end telescopi-
cally applied over said hub, said feed screw at
its other end being provided with an internal con-
40ical clutch surface adapted to receive and co-
operate with the conical clutch surface of said
sleeve, means locking the hub element and feed
screw against axial movement in a direction away
from the sleeve element, and yielding means 45
maintaining the sleeve under pressure to move in
the direction of the feed screw.

5. In a device of the kind described, a power
driven shaft, a rotary grinding disc mounted on
and anchored to the shaft, a fixed grinding disc
50 for cooperation with said rotary grinding disc,
said grinding disc having a cylindrical hub por-
tion, a hollow feed screw telescopicallly applied
over the shaft with one end telescopicallly fitting
over said hub, said screw being formed at its other
55 end to afford an internal conical clutch surface
surrounding the shaft, a sleeve axially slidable on
the shaft and in driving engagement therewith
and formed with an external conical clutch sur-
face for cooperation with the internal clutch sur-
60 face of the screw, and yielding means urging the
sleeve in the direction of the feed screw so as to
maintain the feed screw axially centered on and
in driving engagement with the shaft through
said sleeve. 65

6. In a device of the kind described, a power
driven shaft having a hub portion concentrically
mounted thereon and anchored against axial
movements in respect thereto, a hollow feed screw
telescopicallly applied over said shaft and hav-
70 ing one end seated against said hub element, an
annular friction clutch element carried by the
other end portion of said hollow feed screw, a
cooperating annular friction clutch element ax-
ially slidably mounted on said shaft and engag-
75

ing said first named friction clutch element, means providing positive rotary driving engagement between the shaft and the second named axially slidable friction clutch element and yielding means urging said axially slidable friction clutch element into engagement with its cooperating friction clutch element on the said screw.

7. In a device of the kind described, a feed chamber, a crushing chamber adjacent one end 10 of the feed chamber and opening through a passage located intermediate the top and bottom of the feed chamber, a power driven shaft extending longitudinally through the feed chamber and crushing chamber and being co-axial with said 15 passage, journal bearings for said shaft located outward of the crushing chamber and feed chamber, a rotary grinding disc having a mount hub anchored on said shaft within the crushing chamber, a cooperating stationary grinding disc 20 located in the feed chamber, said rotary grinding disc having an anchoring hub therefrom projecting in the direction of the feed chamber, a hollow feed screw applied over said shaft within the feed chamber and projecting through said 25 passage and mounted on said hub, a sleeve axially slidably mounted on the power driven shaft beyond the other end of said feed screw, means

for positively driving said axially slidable sleeve from said shaft, the adjacent ends of said hollow feed screw and sleeve being provided with cooperating friction clutch surfaces, and yielding means urging said sleeve in the direction of said 5 hollow feed screw.

8. In a device of the kind described, a power driven shaft, a rotary grinding disc mounted on and anchored to the shaft, a fixed grinding disc for cooperation with said rotary grinding disc, 10 said grinding disc having a cylindrical hub portion, a hollow feed screw telescopically applied over the shaft with one end telescopically fitting over said hub, said screw being formed at its other end to afford a conical clutch surface surrounding the shaft, a sleeve axially slidable on the shaft and in driving engagement therewith and formed with a conical clutch surface for cooperation with the clutch surface of the screw, 15 and yielding means urging the sleeve in the direction of the feed screw so as to maintain the feed screw axially centered on and in driving engagement with the shaft through said sleeve.

9. The structure defined in claim 7 in which said cooperating clutch surfaces are conical and 20 one thereof works within the other thereof.

JOHN E. DICK.
